UNITED STATES PATENT OFFICE.

RAYMOND McDONALD ADDISON, OF SAN FRANCISCO, CALIFORNIA.

SAFETY RAZOR.

Application filed April 13, 1925. Serial No. 22,674.

This invention relates to safety razors, and particularly to an armpit safety razor. As is well known, the ordinary safety razor has a straight cutting edge, which is of course the proper contour for ordinary shaving purposes. Such razor, however, is not well adapted for use in shaving armpits, and when so used the end portions only of the blade usually perform the cutting operations. The shaving with such razors is therefore not only very crudely and roughly performed, but the sharp end corners of the blade cut into the flesh and cause bleeding and serious wounds.

As a straight-edge razor is proper for shaving a flat surface, so a curved-edge razor is proper for shaving a curved surface. The contour of an armpit being concave, the provision of a simple and convenient safety razor having a convex contour to co-operate therewith to accurately and neatly shave such surface is the primary object of my invention.

With this and other objects in view, as will hereinafter appear, my invention consists of a safety razor having the features of construction and operation set forth in the following specification and illustrated in the accompanying drawing. In such drawing, annexed hereto and forming a part of this specification, I have shown one specific embodiment of my invention, but it will be understood that the invention can be otherwise embodied, and that the drawing is not to be construed as defining or limiting the scope of the invention, the claims appended to this specification being relied upon for that purpose.

Referring to the figures of the drawing:—

Fig. 1 is a longitudinal sectional view through my improved razor;

Fig. 2 is a top end view thereof;

Fig. 3 is a top end view of the inner guard member;

Fig. 4 is a side elevation of the razor elements in spread-out relation;

Fig. 5 is an enlarged fragmentary detail view showing the relation of the blade and razor;

Fig. 6 is a plan view of a blade for use with the razor;

Fig. 7 is an edge view thereof.

Referring more specifically to the drawing by reference characters, 1 indicates the inner guard or head member having a handle portion 2 projecting therefrom. A co-

operating outer member is indicated at 3, and is provided with a shank 4 adapted to extend through a bore in the handle portion 2. A handle 5 has a bore 6 in the inner end thereof, threaded to co-operate with the threaded end 7 of the shank 4.

The two opposite edges 8 of the inner member 1 are convexly curved as shown in Figs. 2 and 3, and the outer blade-receiving surface 9 thereof is curved transversely and convexly across the member toward and from the said opposite edges. The edges are also slotted at 10 to form a plurality of guard teeth 11, which are grooved at 12 to form outwardly extending projections 13 on the ends of the teeth. The guard teeth 11 taper in depth or thickness from the center of the front of the guard to the sides of the razor.

The two opposite edges of the head 1 are relatively thick and extended downwardly as shown in Figs. 1, 4, and 5 in a manner forming a relatively long transversely sloping surface indicated at 8 in Fig. 5. When the parts are assembled with a blade therebetween this surface forms a long bearing guard which precedes the cutting edge of the blade in the shaving operation and draws the skin taut ahead of the cutting edge of the blade. By referring to Figs. 1 and 5, it will be clear that such surface cooperates in a manner considerably facilitating the shaving operation and greatly reducing the danger of accidental cutting.

The outer and inner surfaces 14 and 15 of the outer member 3 are convexly and concavely curved to co-operate with the contour of the inner member 1. The ends of both members 1 and 3 are formed with straight edges 16, and the outer member is provided with lugs 17 for extending through holes 18 in the razor blade 19 and holes 20 through the member 1. The cutting edges 21 of the blade are convexly curved, preferably to a circular outline, when the blade is flat as shown in Fig. 6.

The forming of the cutting edges 21 of the blade circular is of advantage in many respects, principal among which may be mentioned the ease with which the same can be sharpened. To sharpen the blades, the same are merely mounted on lathe centers or other like rotary supports. Upon rotating the blades thus mounted, the edges 21 can be sharpened merely by engaging the

same with the hone or other sharpening instrument. The blades can of course be easily resharpened in like manner.

The razor as illustrated is exceedingly simple, comprising only three pieces. When these pieces are assembled with a blade held therein, as shown in Fig. 1, the blade is flexed to the contour of the outer surface of the member 1 and held secured between the members 1 and 3. In such position, as shown particularly in Fig. 5, the cutting edges 21 of the blade are directly adjacent and co-operate with the projections 13. It should be noted, however, that while the blade extends over the groove 12 and adjacent the projections 13, the blade does not touch, but is slightly spaced from such projections. Such arrangement provides a free cutting edge guarded by the projections 13 and with a space therebetween for permitting the shavings to pass freely into the groove 12.

As shown in Fig. 2, the outer member 3 is spaced considerably back of the edge of the blade, whereby the same in no way interferes with the cutting action. The convex curvature of the cutting edge of the blade (Fig. 2) in cooperation with the transverse curvature of the blade as shown in Fig. 1, obviously provides a razor which will accomplish the objects of my invention with great facility. It is believed that the construction and operation of my invention will be clear without further description herein.

Having thus described my invention, what I claim as new and desire to secure by Letters Patent is:—

1. A double edged safety razor comprising an inner member having opposite edges thereof convexly curved and formed with guard means for cooperating with the sharp edges of a blade, the outer blade receiving surface of the member being curved convexly-transversely toward and from the said opposite edges, and each such edge being relatively thick and extended to form a relatively long transversely sloping surface, an outer cooperating member, and means for drawing the two members together with a blade held therebetween and with the sharp edges thereof adjacent the said guard means and upper portion of the said sloping edge surfaces, the said sloping surfaces being adapted to cooperate with the sharp edges of the blade to facilitate the shaving operation by drawing the skin taut ahead of the cutting edge of the blade.

2. A double-edge safety razor comprising an inner member having opposite edges thereof convexly curved and formed with guard means for co-operating with the sharp edges of a blade, which sharp edges are convexly curved to a circular outline having a common center when the blade is flat, the outer blade-receiving surface of the member being curved transversely and convexly toward and from the said opposite edges, an outer co-operating member, and means for drawing the two members together with a blade held therebetween and with the sharp edges thereof adjacent the said guard means.

3. A safety razor blade having a cutting edge forming a segment of a circle the center of which is within the body of the blade, the blade having a circular hole therethrough at the said center.

4. A double edge safety razor blade having the two cutting edges thereof respectively on opposite sides of the blade and forming segments of a circle the center of which is disposed therebetween at the center of the blade, the blade having a circular hole therethrough at the said center.

5. A double edged safety razor comprising an inner member having opposite edges thereof convexly curved and formed with guard means for cooperating with the sharp edges of a blade, the outer blade receiving surface of the member being curved convexly-transversely toward and from the said opposite edges, and each edge being relatively thick and extended to form a relatively long transversely sloping surface, an outer cooperating member, and means for drawing the two members together with a blade held therebetween and with the sharp edges thereof adjacent the said guard means and upper portion of the said sloping edge surfaces, the said sloping surfaces being adapted to cooperate with the sharp edges of the blade to facilitate the shaving operation and the relatively thick edges tapering in thickness from the center to the ends thereof and gradually decreasing the length of the sloping surfaces.

6. A double edged safety razor blade of approximately circular form having opposite cutting portions forming segments of a circle the center of which is the center of the blade, said blade being flexed to a cylindrical surface.

RAYMOND McDONALD ADDISON.
